United States Patent Office

WILLIAM H. WALTON, OF BROOKLYN, NEW YORK.

Design No. 4,802, dated April 11, 1871.

DESIGN FOR PRINTED MATERIAL FOR GORED SKIRTS.

The Schedule referred to in these Letters Patent and making part of the same.

To all whom it may concern:

Be it known that I, WILLIAM H. WALTON, of Brooklyn, in the county of Kings and State of New York, have invented a new, useful, and original Design for Printed Material for Gored Skirts; and I do hereby declare that the following is a full, clear, and exact description thereof, reference being had to the accompanying drawing and the letters of reference marked thereon.

My invention consists in a new and useful design for printing a roll or piece of muslin or other woven fabric in a series of patterns for gored skirts, so that the entire piece may be cut into gores, of the proper and uniform shape to be made up into skirts, by following the lines printed thereon, without waste of material, and so that the skirt, when made up, will have a continuous and uniform border around its lower edge, as hereinafter described.

In the accompanying drawing—

Figure 1 represents a piece of muslin partially unrolled, printed in pattern-sections, pursuant to my invention; and

Figure 2, a side view of the same.

The roll of muslin is shown at *a*;

b represents the design printed thereon; and *c*, lines printed at the same time, to indicate where the cloth is to be cut.

The curved lines *c* divide the cloth in such a manner that each division is a segment of a circle, and the design is printed alike on all the divisions, so that when the gores are sewn together the design will match all around the skirt, forming a continuous and uniform border.

On each gore or division a sufficient space is left clear on each side of the printed design where the gores are to be sewn together for forming the same without turning in any portion of the printed design.

The piece of muslin is printed in sections of uniform length and shape, and each of said sections is so printed as to be divided longitudinally into two gores precisely alike, and the bottom or lower edge of each gore is so curved as to form the segment of a circle to which the sides are radial.

What I claim as my invention, and desire to secure by Letters Patent, is—

The within-represented shape or configuration of a series of patterns for gored skirts, printed upon a piece of muslin or other woven fabric, substantially as herein shown and described.

WILLIAM H. WALTON.
